FIG. 1

FIG. 2

FIG. 3

Figure 1 is a perspective view of a multi-compartment beverage dispensing carton, showing our new design.

Fig. 2 is a top plan view thereof.

Fig. 3 is an enlarged fragmentary perspective view of the top front left corner thereof, showing the cap removed therefrom.

The rear and side not shown are the same as the front and side illustrated in the drawing. The horizontal lines on the handle in Figs. 1 and 3 illustrate score lines.

The design for the unitary multi-compartment beverage dispensing carton disclosed is characterized by the top portions having the configurations and arrangement shown.

We claim:

The ornamental design for a multi-compartment beverage dispensing carton, as shown and described.
